(57) **CLAIM**

The ornamental design for a vehicle dent guard, as shown and described.

DESCRIPTION

FIG. 1 is a perspective view of a vehicle dent guard showing my new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines in the drawings show symbolic breaks in the length of the vehicle dent guard. Neither the break lines nor the appearance of any portion of the vehicle dent guard between the break lines form part of the claimed design.
